[57] CLAIM

The ornamental design for clock body, as shown and
described.

DESCRIPTION

FIG. 1 is a front elevational view of a glass clock body
showing my new design;

FIG. 2 is a top plan view thereof;

FIG. 3 is a right side elevational view thereof, the left
side being a mirror image thereof;

FIG. 4 is a bottom view thereof;

FIG. 5 is a rear elevational view thereof; and,

FIG. 6 is a cross-sectional view thereof as taken along
line 6—6 of FIG. 5.The broken line showings of FIGS. 1-4 are environ-
mental only and form no part of the claimed design.*Fig. 1**Fig. 3**Fig. 2**Fig. 4**Fig. 5**Fig. 6*A reference line with an arrow pointing to the right, labeled with the number 6.
